HAND RULE PUNCH FOR PRINTERS

Albert E. Neudauer, Oklahoma City, Okla.

Application September 23, 1952, Serial No. 311,136

4 Claims. (Cl. 164—10.5)

This invention relates to new and useful improvements in punching devices and the primary object of the present invention is to provide a device for punching slug accommodating slots in printing rules.

Another important object of the present invention is to provide a punch that is secured to a graduated base strip so that a printing rule may be held upon the base strip and provided with a slot as the punch is actuated.

A further object of the present invention is to provide a hand rule punch for printing rules involving a stop member that is longitudinally adjustably secured for a printing rule, whereby slots may be cut in the rule at preselected space intervals.

A still further aim of the present invention is to provide a hand rule punch for printers which is extremely simple and practical in construction, strong and reliable in use, small and compact in structure, efficient and durable in operation, inexpensive to manufacture, and otherwise well adapted for the purposes for which the same is intended.

Other objects and advantages reside in the details of construction and operation as more fully hereinafter described and claimed, reference being had to the accompanying drawings forming part hereof, wherein like numerals refer to like parts throughout, and in which:

Figure 1 is a perspective view of the present invention;

Figure 2 is a perspective view showing printing rules processed by the present invention, operatively engaged with printing slugs;

Figure 3 is an enlarged fragmentary transverse vertical sectional view taken substantially on the section line 3—3 of Figure 1 and showing a printing rule in position to the base strip and punch;

Figure 4 is a perspective view of a finished printing rule after the same has been provided with slots;

Figure 5 is a group sectional view of the upper and lower punch elements used in the invention;

Figure 6 is a plan view of the upper punch element taken substantially on the section line 6—6 of Figure 5;

Figure 7 is a fragmentary perspective view of one type of slug used in conjunction with the printing rules slotted by the present invention;

Figure 8 is a modification of the printing slug; and

Figure 9 is a further modification of the printing slug.

Referring now to the drawings in detail, wherein for the purpose of illustration, there is disclosed a preferred embodiment of the present invention, the numeral 10 represents an elongated rigid base strip having its rear longitudinal edge turned upwardly to form a guide ledge or flange 12. The upper face of the strip 10 is provided with longitudinally spaced, transverse graduations forming a scale 14.

The end portions of the strip 10 are provided with apertures 16 and will receive fasteners 18 which are engaged in the upper ends of cylindrical supporting feet or pins 20. The flat lower ends of the pins 20 are intended to rest upon a horizontal surface to support the strip 10 in a horizontal position.

2

The flat jaw end 22 of a lower lever or handle 24 is suitably secured to the undersurface of strip 10, at substantially the center of the strip 10. Lever 24 extends at right angles to the strip 10 and is channel shaped in cross section to include spaced parallel vertical flanges 26 between which there is received a jaw portion 28. A horizontal pin 29 extends through flanges 26 and portion 28 to permit swinging or locking movement of jaw portion 28 relative to the jaw end 22.

An upper channel shaped lever or handle 30 overlies and faces the lever 24 and includes a forward bifurcated end 32 that is pivoted, as at 34, to the rear end of jaw portion 28. A pitman or link 36 forming a fulcrum is terminally pivotally attached between the flanges of the levers 24 and 30. A coil spring 38 is biased between the levers 24 and 30 to urge the lever 30 raised relative to the lever 24 and hence the jaw portion 28 spaced from the strip 10 and jaw end 22.

The forwardly extending flat forward end 40 of jaw portion 28 is provided with a recess 42 that accommodates the reduced upper end portion 44 of a male die or punch element 46 having a T-shaped cutting lug 48 on its lower face. A screw 50 extends downwardly through an aperture in the end 40 and is threaded into a recess 52 in the punch element 46 to secure the central part of punch element 46 against the flat undersurface of the end 40.

T-shaped lug 48 is progressively reduced in thickness from front to rear, as shown in Figure 3, so that as the end 40 is moved downwardly, the lower face of lug 48 will be substantially parallel to the base strip 10.

The strip 10 is formed with a central opening 54 that registers with an opening 56 in the jaw end 22. The reduced lower end 58 of a female tubular die or punch element 60 is extended through opening 54 and into opening 56. The punch element 60 is provided with a T-shaped bore 62 that will accommodate the T-shaped lug 48 as the punch element 46 is moved downwardly relative to base strip 10.

A pair of downwardly facing channels 64 overlie the upper face of the base strip 10 and parallel the flange 12. The channels 64 are provided with attaching flanges 66 that are apertured to receive the upper ends of threaded studs or lugs 68. Studs 68 are suitably fixed on their lower ends to the strip 10 and extend upwardly from strip 10 to receivably engage wing nuts 70.

A stop member 72 is slidably adjustably mounted on the base strip 10 and coacts with flange 12 in retaining a printing rule R in position to the punch. Stop member 72 includes a rod 74 having a transverse stop 76 at one of its ends that extends perpendicular to the flange 12. The rod 74 is slidably received in the channels 64 and is clamped against the upper face of the strip 10 by the channels as the nuts 70 are tightened, in order to adjust the rod 74 longitudinally of the strip 10 for locating the stop 76 relative to a predetermined graduation of scale 14.

In practical use of the present invention, a printing rule R is placed over the strip 10 with one of its longitudinal edges resting against flange 12 and with one of its end edges engaging the stop 76. The beveled longitudinal edge E of rule R overlies the punch element 60 and underlies the male punch element 46. As the handle 30 is forced downwardly toward the handle 24, jaw portion 28 will be rocked to force the T-shaped lug 48 through the rule R and into the punch element 60. The rule R is moved longitudinally relative to the strip 10, after the stop member 72 has been adjusted, so that a plurality of longitudinally spaced T-shaped slots S may be formed in the beveled edge E of the rule R.

After a predetermined number of the rules R have been slotted, the flanges of T-shaped printing slugs are extended through registering slots in a group of the

rules, as shown in Figure 2. The slugs may be of various types as shown in Figures 7, 8 and 9 with the printing facings or edges thereof coplanar with the beveled edges E of the rules R. The printing face F₁ of the slug S₁ shown in Figure 7 is V-shaped to permit printing of two parallel relatively thin lines; the printing face F₂ of the slug S₂ in Figure 8 is flat to print a wide line; and the printing face F₃ of the slug S₃, shown in Figure 9, is beveled to print a thin single line.

In view of the foregoing description taken in conjunction with the accompanying drawings it is believed that a clear understanding of the device will be quite apparent to those skilled in this art. A more detailed description is accordingly deemed unnecessary.

It is to be understood, however, that even though there is herein shown and described a preferred embodiment of the invention the same is susceptible to certain changes fully comprehended by the spirit of the invention as herein described and the scope of the appended claims.

Having described the invention, what is claimed as new is:

1. A hand rule punch for printers, said punch comprising an elongated base strip having graduations thereon, a lever having a jaw end secured to and under the strip, a second lever pivoted to the first lever and having a jaw portion overlying the jaw end, a male punch element secured to the jaw portion, a female punch element secured to the jaw end and extending upwardly through said strip, and a stop member slidably adjustably mounted on said strip to limit sliding movement of a rule relative to the punch elements.

2. A hand rule punch for printers, said punch comprising an elongated base strip having graduations thereon, a lever having a jaw end secured to and under the strip, a second lever pivoted to the first lever and having a jaw portion overlying the jaw end, a male punch element secured to the jaw portion, a female punch element secured to the jaw end and extending upwardly through said strip, and a stop member slidably adjustably mounted on said strip to limit sliding movement of a rule relative to the punch elements, said base strip having an upstanding flange disposed alongside of said stop member and forming a guiding surface for a rule that is to be punched by the punch elements.

3. A hand rule punch for printers, said punch com-

prising an elongated base strip having graduations thereon, a lever having a jaw end secured to and under the strip, a second lever pivoted to the first lever and having a jaw portion overlying the jaw end, a male punch element secured to the jaw portion, a female punch element secured to the jaw end and extending upwardly through said strip, a stop member slidably received on the strip and including a rod, a pair of channels having attaching flanges, threaded studs fixed to and extending upwardly from said base strip, said attaching flanges having apertures receiving the studs, and nuts threaded on said studs for clamping the attaching flanges against said base strip, said channels slidably receiving the rod and clamping the rod against the base strip as the nuts are tightened to clamp the attaching flanges against the base strip.

4. A hand rule punch for printers, said punch comprising an elongated base strip having an upper face with graduations thereon, a lower lever having a jaw end secured to the undersurface of said base strip and projecting laterally from said base strip, an upper jaw portion pivoted to the lever and disposed over the jaw end, a link carried by said lever, a hand grip pivoted to the link and also pivoted to the jaw portion for moving the latter toward the jaw end, a male punch element fixed to the jaw portion, a female punch element fixed to the jaw end and extending upwardly from the upper face of said base strip, and means carried by the base strip for retaining a rule forming strip relative to the punch elements as the same are actuated to punch the rule forming strip, said means including an upstanding longitudinal flange on the base strip and a stop member slidably adjustably disposed on the upper face of said base strip and having a portion disposed perpendicular to said flange.
